UNITED STATES PATENT OFFICE.

SAM FORD, OF TOLEDO, OHIO.

COMBINED BED AND TRUNK.

Original application filed August 5, 1927, Serial No. 210,876 Divided and this application filed February 7, 1928. Serial No. 252,593.

This invention relates to an article of furniture, such as a bed, but more particularly to a combined bed, wardrobe and trunk, and is a division of my application Serial No. 5 210,876, filed August 5, 1927, and has for its object to provide, in a manner as hereinafter set forth a bed including a head element and a foot element connected together by side rails and with the head element constructed 10 and arranged to function as a trunk and a compartment for the storage of valuables.

A further object of the invention is to provide, in a manner as hereinafter set forth, an article of furniture in the form of a 15 single unit and functioning as a bed, a normally closed trunk and a normally closed storage compartment and further with said unit including means to provide for conveniently opening the trunk and storage 20 compartment.

Further objects of the invention are to provide, in a manner as hereinafter set forth an article of furniture in the form of a 25 single unit comprising a bed, a storage compartment and a trunk and with the unit comparatively simple in its construction and arrangement, strong, durable, compact, thoroughly efficient in its use, not impairing the appearance of the room in which it is used, 30 readily assembled, conveniently disassembled when required, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood 40 that changes, variations and modifications can be resorted to which fall within the scope of the claims hereunto appended.

In the drawings wherein like reference characters denote corresponding parts throughout the several views:

Figure 1 illustrates in side elevation an article of furniture in accordance with this invention.

Figure 2 is a fragmentary view in vertical section of the unit, illustrating the trunk forming a part of the head element in open position.

Figure 3 is a rear elevation of the head element of the unit.

Figure 4 is a sectional plan of the head element and illustrating the trunk thereof in open position.

Figure 5 is a fragmentary view in elevation of the head element and further illustrating in longitudinal section the trunk forming a part of the head element and with the trunk in closed position.

Figure 6 is a fragmentary view in vertical section of the upper portion of the head element.

Figure 7 is a fragmentary view in side elevation of the head element and further illustrating the trunk forming a part thereof with its body extended to open position and with the lid or cover partly shifted from the 70 body of the trunk and in an upward direction.

An article of furniture in the form of a unit and in accordance with this invention is a combined bed, wardrobe, trunk and storage compartment and said unit includes a pair of side rails A, B, a head element C and a foot element D. The side rails A, B, 75 detachably connect with the elements C and D for not only coupling them together but for 80 maintaining them in spaced relation. The head element C is of greater height than the foot element D although it is to be understood that the elements C and D can be constructed of any desired height.

As the side rails A and B are of like construction, but one will be described, as the description of one will apply to the other. The side rails are oppositely disposed with respect to each other and are of angle shaped 90 cross section and each side rail comprises a vertically disposed portion 1 and a horizontally disposed portion 2 and with the latter extending inwardly at right angles with respect to the bottom of the former. 95 Secured to the inner face of the vertical portion 1, in proximity to each end thereof, and extending down through the horizontal portion 2, as well as projecting a substantial distance therebelow, is a vertically disposed 100 coupling pin 3, which has its upper portion fixedly secured to the inner face of the vertical portion 1 of the rail. The vertical portion 1 of each of the rails, has projecting

from its outer face, in proximity to each end thereof, a headed coupling lug 4. The pins 3 and lugs 4 coact with the elements C and D for the purpose of detachably connecting 5 the side rails therewith, whereby the elements C and D will be coupled together and maintained in spaced relation and the manner in which the said pins and lugs associate with said elements C and D will be 10 presently referred to. The side rails can be of any appropriate length desired and any suitable cross sectional area. When the side rails are mounted in position relative to the elements C and D, they abut the inner 15 faces of said elements, in a manner as shown in Figure 2.

The head element C includes a pair of vertically disposed spaced posts or standards 5, 6, and each of which has connected to its 20 lower end a castor 7. The posts 5, 6, are of appropriate height and have the lower end portions thereof tapered as indicated at 8. Arranged between the posts 5, 6, at the upper 25 ends of the tapered portions 8 is a horizontally disposed combined brace and connecting member 9 having its side edges flush with the front and rear edges of the posts. The width of the member 9 corresponds to the width of either of the posts and secured 30 between the posts a substantial distance above the member 9, is a flat horizontally disposed combined brace and connecting member 10, and which is flush with the forward and end edges of said posts. Positioned 35 between the members 9 and 10, and flush with the forward edges of the posts, is a vertically disposed wall forming member 11 which extends from the post 5, to the post 6, and abuts against the upper face of 40 the member 9 and against the lower face of the member 10. The thickness of the member 11 is materially less than the width of either of the members 9, 10. Arranged between the members 9 and 10 and flush with 45 the rear edges of the posts 5, 6, is a wall forming member consisting of a stationary lower section 12, and a hinged upper section 13 which constitutes a door. The hinged connection between the sections 12 and 13 is indicated at 14. The sections 12 and 13 50 extend from the post 5 to the post 6 and abut the upper face of the member 10. The section 13 extends from the post 5 to the post 6 and is detachably connected with the member 10 by a latch 15. The sections 12 and 13 are of a thickness materially less 55 than the width of the members 9 and 10. The posts 5, 6, in connection with the members 9, 10, the member 11 and the sections 12, 13 provide a storage compartment 16 and entrance is had thereto by means of shifting the section 13 outwardly upon the hinged connection 14. The compartment 16 is provided for the storing of valuables and access 60 can only be had thereto when the head ele-

ment C is swung a sufficient distance from the wall so that a person can operate the latch 15 for the purpose of releasing the section 13 whereby the latter can be swung outwardly. The entrance to the compartment 16 is arranged at the rear of the head element C and when the article of furniture is used said section 13 opposes that wall which the head element C is arranged in close proximity to. By this arrangement 75 it reduces surreptitious entrance to the compartment 16 to a minimum.

Arranged between the posts 5, 6, in proximity to their upper ends, is a flat horizontally disposed combined brace and connecting member 17 having secured upon its top and flush with its forward edge an ornamenting head piece 18 which is disposed vertically and extends from the post 5 to the post 6. The member 18 is secured in 85 any suitable manner to the posts 5, 6 and member 17. That part of the element C between the members 10 and 17 is open and pivotally supported therein is a trunk, container or receptacle referred to generally at 90 19 and which includes a body portion comprising a bottom 20, side walls 21, 22, end walls 23, 24 each provided with a rectangular opening 25 and a guide strip 26 which is secured upon the top edge of the side wall 95 21, projects inwardly therefrom and extends from the end wall 23 to the end wall 24. The upper face of the strip 26, at the rear thereof, is mortised as at 27 to provide a seat. The side wall 21 is the outer side wall and 100 the side wall 22 the inner side wall and the bottom 20 and end walls 23, 24 project rearwardly from the side wall 22, see Figure 4. Connected to the posts 5, 6, and arranged above and in proximity to the member 10, 105 and further in proximity to the forward edges of the posts, is a bar 28, upon which the lower part of each of the rearwardly extending portions of an end wall is pivoted, 110 see Figures 4 and 7. The rod 28 is positioned in close proximity to the upper face of the bottom 20. Secured upon the upper face of the bottom 20, abutting against the rear side wall 22 and extending from one end wall to the other is a guide strip 29.

Arranged within the body portion 19 is a tray or drawer 30 provided at each end with a handle 31. The drawer or tray 30, slidably mounted upon the bottom 20, is arranged below the strip 26 and slides 120 against the guide strip 29. The tray 30 can be withdrawn through an opening 25 from either end of the body portion 19. Hinged to the rear side wall 22, as at 32 is a lid or cover 33 for the open top body 125 portion 19. The lid or cover 33 is rabbeted as at 34, to engage the rabbet 27 when the lid or cover is in closure position with respect to the open top of the body portion 19. The lid or cover 33 also provides means for 130

arresting the shifting of the tray from the body portion 19, in either direction, unless the lid or cover is swung to open position and for this purpose the lid or cover 33 is formed at each end with a depending flange 34, which when the lid 33 is mounted in closure position extends into the tray, to the position shown in Figure 6 whereby the flanges 34 will be arranged inwardly of the ends of the tray and will prevent the latter from being pulled outwardly in either direction with respect to the body portion 19 through the end walls 23, 24 of the latter.

Connected to the strip 26 are flexible suspension members 35 and which extend between the posts 5, 6. The lower ends of the suspension members 35 are fixedly secured to the strip 26 as at 36 and the upper ends of the members 35 are secured to the rear 20 edge of the member 17 as at 37. The bottom 20 of the body portion 19 is arranged in a manner whereby it will be in alignment with the wall forming member 11 when the trunk is swung to an upward position to be arranged between the posts 5, 6 and to project rearwardly therefrom, see Figure 6. The lid or cover 33 has a handle 38 and is secured in closure position, with respect to the body portion 19, by a pivoted latch 39 which is carried by the strip 26 and is shiftable to overlap the cover when the latter engages the rabbet 27. The member 18 is provided with a resilient, depending latch 40 for latching the lid or cover 33 in an open position with respect to the body portion 19, see Figure 2. The end walls 23, 24 are provided with projections 41 which seat on the member 10 when the trunk is closed and positioned within the opening between the members 10 and 17, see Figure 6. The bottom 20 is provided with a latch 42 which engages with a keeper 43, carried by the member 17 at the front thereof and the latch 42 provides means for maintaining the trunk 45 when it is swung into the opening formed between the members 10 and 17, see Figure 6. When the trunk is in the position shown in Figure 6, the flexible suspension members 35 are arranged at the rear of the element C and in this connection see Figure 6. The pivot rod 28 is so arranged that when swinging the trunk forwardly it will not engage the wall against which the head element 6 opposes.

55 The end walls 23, 24 of the body portion 19 of the trunk, have secured therein bearing sleeves 76 for the pivot rod or bar 28, see Figure 4.

The forward edges of the posts 5, 6 of the element C and each of the posts 6' of the element D, at an appropriate distance above the lower end of each thereof, has secured thereto superposed socket forming members 44 and 45. The members on the element C 65 are forwardly directed and on the element

D rearwardly directed. The members 44 are arranged above the members 45. The member 44 receives a headed lug 4 and the member 45 a pin 3. A member 44 and a member 45 associate with each end of each 70 of the side rails 45 and by this arrangement the two side rails are detachably connected to the head or foot elements. The pins 3 and headed studs 4 and socket forming members 44, 45 are constructed in a manner 75 to provide a wedging action therebetween when the side rails are coupled to the head element C and foot element D. The sockets formed by the members 44 are disposed at right angles to the sockets formed by the 80 members 45. The posts 6' of the element D are provided with castors 7'.

It is thought the many advantages of an article of furniture in the form of a unit and functioning as a bed, trunk and storage 85 compartment, can be readily understood, and although the preferred embodiment of the invention is as illustrated and described, yet it is to be understood that changes in the details of construction can be had which 90 will fall within the scope of the invention as claimed.

What I claim is:

1. In a bed, a head element including means to provide a pivoted trunk and suspension members for the trunk, said trunk consisting of an open top body portion provided with an opening at each end, a tray within the trunk and shiftable outwardly through either of said openings, and a lid 95 for closing the trunk, said lid including means to prevent the shifting of the tray through either of the openings when the lid is in closed position.

2. In a bed, a head element comprising a 105 pair of spaced posts, a trunk including an open top body portion having a normally latched hinged lid for closing said open top, means for pivotally supporting the lower corners of said body portion between and above the lower ends of the posts, suspension means between the posts and trunk when the latter is extended forwardly with respect to the posts, and means for latching the trunk in non-extended position between the 110 posts, said trunk further including a tray removable through each end of said body portion, and said lid including means to prevent the removal of the tray when the lid is in closure position.

3. In a bed a head member including a pair of spaced posts, a storage element arranged between the posts and including a pair of receptacles, one shiftable laterally with respect to and supported by the other, 125 the said other section having a shiftable closure therefor, and means carried by the posts for pivotally supporting said element.

4. In a bed a head member including a pair of spaced posts, a storage element ar- 130

ranged between the posts and including a pair of receptacles, one shiftable laterally with respect to and supported by the other, the said other section having a shiftable closure therefor, means carried by the posts for pivotally supporting said element, a cross member positioned between and se-

cured to the posts at the upper ends thereof, and suspension means for said element, said means connected to said cross member and 10 to said element.

In testimony whereof, I affix my signature hereto.

SAM FORD.
